UNITED STATES PATENT OFFICE.

CARL A. WENDELL, OF JOLIET, ILLINOIS.

DRIER.

1,190,829.

Specification of Letters Patent. Patented July 11, 1916.

Application filed June 12, 1915, Serial No. 33,792. Renewed May 19, 1916. Serial No. 98,670.

To all whom it may concern:

Be it known that I, CARL A. WENDELL, a citizen of the United States, residing at Joliet, in the county of Will and State of Illinois, have invented a certain new and useful Improvement in Driers, of which the following is a specification.

My invention relates to centrifugal drying machines adapted for the purpose of extracting moisture from materials, and in the particular instance here illustrated I have shown an apparatus designed for drying coal.

It is illustrated in the accompanying drawings wherein—

Figure 1 is a vertical section; Fig. 2 a plan view with parts broken away; Fig. 3 a detail sectional view on the line 3—3 of Fig. 2; Fig. 4 a detail sectional view on the line 4—4 of Fig. 1; Fig. 5 is a bottom view of the parts shown in Fig. 3.

Like parts are indicated by the same letter in all the figures.

A, A are the supports and braces which together constitute a frame for the support of the several parts of my machine.

B is a driving pulley on the upper end of the shaft B¹ to which is keyed a gear wheel B² which is in mesh with and drives a gear wheel B³ on the vertical shaft B⁴ suitably supported in the bearings B⁵, B⁶ on the frame. This shaft carries another gear wheel C which meshes with a small gear C¹ on the hollow shaft C² which surrounds the solid shaft B¹.

Mounted on the hollow shaft C² is the feed cylinder C³ from which radiate the feed chutes C⁴, C⁵ and above which are placed so as to discharge into said cylinder is the supply chute C⁶.

Mounted on the frame at the lower end of the hollow shaft C² is an umbrella shaped collar D which supports the chute C⁴ and has an anti-friction bearing D¹ on top of the second umbrella-shaped collar D². This collar is keyed to the shaft B¹ and both shaft and umbrella-shaped collar D² are properly supported in any desired manner. The collar D² carries a receptacle composed of the walls D³, bottom D⁴, screen sections E, E and top D⁵.

D⁶ is a fixed casing mounted in any desired manner, as for example, on the material box D⁷, and it preferably extends upwardly to near the feed cylinder C³ to inclose the parts.

The screens E, E are arranged in sections about the periphery of the rotating material receptacle. Each screen may or may not, as the case may be or the requirements of particular machines or materials may suggest, be inclosed in a compartment by means of side walls. In the particular form of the apparatus shown here I do not show any such pocket.

E¹ is that portion of the floor or bottom of the receptacle which lies beneath the screen E and E² is an annular portion of the top of the receptacle which lies above the screen E. The bottom E¹ is provided with an aperture E³ through which passes the pin E⁴ with an enlarged head E⁵. Inwardly projecting from the head E⁵ is the arm E⁶ which lies in the path of the roller E⁷ on the downwardly and laterally bent arm E⁸ which is secured to and travels with the spout. On the lower end of the pin E⁴ and below the bottom E¹ is a laterally projecting arm E⁹, whence leads a chain E¹⁰ to an arm E¹¹ downwardly projecting from the lower edge of the screen frame E¹². Outwardly projecting from the pin E⁴ is another arm E¹³ at the outer end of which is a weight E¹⁴. By this arrangement the parts tend to remain in the position shown in Fig. 3 because the centrifugal effect on the ball E¹⁴ overcomes the tendency of the screen to move outwardly to the position shown in dotted lines responsive to centrifugal force.

F is a lip projecting upwardly and outwardly from the lower end of the screen E and overlying a downwardly projecting lip F¹ on the annular plate F², between which and the outer edge of the plate E² is an outwardly opening channel F³ for the escape of the water.

I have not carefully shown the particular details of the construction of these several parts because they may, of course, be made in any desired way. My drawing is rather a diagrammatic than a working drawing. Nor do I wish to be limited to the particular size, shape and arrangement of the several parts illustrated and described, as they could be greatly altered without departing from the spirit of my invention.

The use and operation of my invention are as follows: I prefer to use two feed chutes with a considerable number of separate or individual screen sections. The screen and chute are driven differentially so that the chute gradually advances its posi-

tion with reference to the screens while both are rotating together in the same direction. As any given chute or spout advances its downwardly and laterally, or forwardly in the direction of rotation, bent arm E^8 approaches the arm E^6 and when the roller E^7 on the arm E^8 engages the arm E^6 it rotates the pin E^5 , swinging the weight E^{14} on its pivot and releasing the chain E^{10} so that centrifugal force will cause such screen, being the screen in advance of the spout, to yield to centrifugal force and rise to the position shown in dotted lines in Fig. 3. Thus a section of the dried material in the ring 15 of material or a pocket full of such dried coal, if the ring be divided into pockets, will be discharged by centrifugal force downwardly and outwardly along the screen E into the coal hopper or receptacle below. 20 This action takes place intermittently, although for practical purposes continuously, along the ring in connection with each spout or chute. During the entire operation, except when such screen is forced into 25 the position shown in Fig. 3, the water will be expelled from the coal or other material through the screen by centrifugal force and will pass up over the lips or deflecting plates F and F^1 and across the annular plate 30 F^2 into the outer receptacle F^4 , whence it may be discharged through the pipe F^5 . As soon as the differential rotation of the parts has moved the chute or spout forwardly, the roller E^7 will release the arm 35 E^6 , whereupon all the parts will resume the position shown in Fig. 3, and immediately thereafter the advancing chute will fill such empty space or pocket with moist coal or material. The apparatus is so constructed 40 and timed that the drying process will have been completed by the time the feed chutes have made one-half of one revolution as compared with the screens, whereupon the same action as above described will take 45 place and the dry material will be discharged and its space immediately thereafter occupied with wet material. The screen E is sufficiently tilted to furnish a wide outlet and an easy flow for the centrififugally propelled material out of the material or drying receptacle into the material box. 50

In the preferred form of my device here illustrated the screen E is in the first instance set at an angle to the vertical, although, of course, this is not essential. If the screen be in a vertical position when it is tripped, it will move to an inclined position and thus centrifugal force will have 55 full opportunity to expel the material from beneath the inclined screen.

In the preferred form of my device there are two spouts, but of course any number of spouts could be used and the speed of rotation could be varied and the particular de-

tails of the device here shown for tripping or tilting or permitting the screen to tilt could be greatly varied without departing from the spirit of my invention. If the feed spout is moving slower than the ring of material then the dumping means must be provided to dump behind it stated in terms of its movement with respect to the ring of material. In either event, however, the dumping takes place before or in advance of the discharge of material to the dumped or empty portion of the ring, that is to say, the ring is first cleared of material at a certain point and then subsequently wet material is fed to that point. In the claims 70 I have described the discharged section as being in advance of the fed section, that is to say, the discharged section is always dumped before the feeding spout reaches the position from which it discharges wet 75 material to the previously emptied zone.

I claim:

1. In a centrifugal drier a screen, a feed chute adapted to deliver material to one side of the screen, means for swinging the screen to permit the material to escape and a water deflecting plate attached to and moving with the screen. 90

2. In a centrifugal drier an inclined screen, a feed chute adapted to deliver material to one side of the screen, means for swinging the screen to permit the material to escape and a water deflecting plate attached to and movable with the screen. 95

3. In a centrifugal drier a series of screen 100 sections, a feed chute adapted to deliver material to one side of each of such sections, means for swinging the sections to permit the material to escape and a water deflecting plate attached to and moving with the screen. 105

4. In a centrifugal drier a series of inclined screen sections, a feed chute adapted to deliver material to one side of each of said 110 sections, means for swinging the screen sections to permit the material to escape and a water deflecting plate attached to and moving with each screen section.

5. In a centrifugal drier a screen, a feed chute adapted to deliver material to one side of the screen, means for swinging the screen to permit the material to escape and a water deflecting plate attached to and moving with the screen, a water box open toward the outer side of the screen and a material box open toward the other side of the screen 120 when the latter is tilting.

6. In a centrifugal drier an inclined screen, a feed chute adapted to deliver material to one side of the screen, means for swinging the screen to permit the material to escape and a water deflecting plate attached to and movable with the screen, a water box open toward the outer side of the screen and a material box open toward the other side of the screen 125 when the latter is tilting.

7. In a centrifugal drier a series of screen sections, a feed chute adapted to deliver material to one side of each of such sections, means for swinging the sections to permit the material to escape and a water deflecting plate attached to and moving with the screen, a water box open toward the outer side of the screen and a material box open toward the other side of the screen when the latter is tilting.
8. In a centrifugal drier a series of inclined screen sections, a feed chute adapted to deliver material to one side of each of said sections, means for swinging the screen sections to permit the material to escape and a water deflecting plate attached to and moving with each screen section, a water box open toward the outer side of the screen and a material box open toward the other side of the screen when the latter is tilting.
9. A centrifugal drier containing a screen, a feed chute adapted to deliver material to one side of the screen, means for rotating them differentially and means for swinging the screen to permit the material to escape, a water box open toward the outer side of the screen and a material box open toward the material side of the screen when the latter is tilting.
10. A centrifugal drier containing an inclined feed chute adapted to deliver material to one side of such screen, means for rotating them differentially and means for swinging the screen to permit the material to escape, a water box open toward the outer side of the screen and a material box open toward the material side of the screen when the latter is tilting.
11. A centrifugal drier containing a series of screen sections, a feed chute adapted to deliver material to one side of each of such screen sections, means for rotating the screens and chute differentially and means for tilting the screen sections to permit the material to escape, a water box open toward the outer side of the screen and a material box open toward the material side of the screen when the latter is tilting.
12. A centrifugal drier containing a series of inclined screen sections, a feed chute adapted to deliver material to one side of each of such sections, means for rotating the screen sections and chute differentially and means for tilting the screen sections to permit the material to escape, a water box open toward the outer side of the screen and a material box open toward the material side of the screen when the latter is tilting.

In testimony whereof, I affix my signature in the presence of two witnesses this 24th day of May 1915.

CARL A. WENDELL
